COMBINED TELEPHONE STAND AND FLASHLIGHT HOLDER

Filed Aug. 31, 1936

Inventor:
Manley J. Gerrells

UNITED STATES PATENT OFFICE

102,427

DESIGN FOR A COMBINED TELEPHONE STAND AND FLASHLIGHT HOLDER

Maude J. Gerrells, San Antonio, Tex.

Application August 31, 1936, Serial No. 64,645

Term of patent 3½ years

To all whom it may concern:

Be it known that I, Maude J. Gerrells, a citizen of the United States, residing at San Antonio, in the county of Bexar and State of Texas, have invented a new, original, and ornamental Design for a Combined Telephone Stand and Flashlight Holder, of which the following is a specification, reference being had to the accompanying drawing, forming part thereof.

The figure is a perspective view of a combined telephone stand and flashlight holder, showing my new design.

I claim:

The ornamental design for a combined telephone stand and flashlight holder, as shown.

MAUDE J. GERRELLS.
